UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

STITCH-FORMING MECHANISM FOR SEWING-MACHINES.

1,280,680.

Specification of Letters Patent.

Patented Oct. 8, 1918.

Application filed November 30, 1915. Serial No. 64,221.

To all whom it may concern:

Be it known that I, ALBERT H. DE VOE, a citizen of the United States, residing at Westfield, in the county of Union and State 5 of New Jersey, have invented certain new and useful Improvements in Stitch-Forming Mechanism for Sewing-Machines, of which the following is a specification, reference being had therein to the accompanying drawings.

This invention has for its object to provide means for laying one or more threads across the path of a plurality of needles in the formation of a cross thread stitch similar to that illustrated in the patent to Berger, No. 1,060,526, of April 29, 1913.

In the aforesaid patent two coöperative implements are employed for laying the cross threads in front of the path of the needles, 20 each implement being carried by a rocker having a link connection with a second rocker fulcrumed upon the head of the sewing machine and given operative movements from a crank-stud on the oscillatory actuating shaft by means of a pitman. The two rockers which serve as carriers for the thread laying implements are pivotally mounted on the presser-bar, so that it is necessary to provide two distinct universal link connections between them and the rocker mounted 25 on the frame.

By means of the present improvement all of the driving members for the thread laying implements are mounted directly upon the presser-bar with the exception of a sliding driving connection on the needle-bar actuating shaft. Furthermore the carrier for one implement receives motion from its oscillatory supporting shaft and transmits motion directly to its companion implement carrier, thus reducing the number of parts to a minimum.

The improvements are applied to the machine provided with the usual reciprocating needle-bar mounted in the head of the overhanging arm parallel with an endwise movable presser-bar. Clamped upon the presser-bar near its lower end is the collar of an arm which supports a depending vertical stud 45 affording a pivotal support for a short rocking carrier arm for one of the thread laying implements. The presser-bar is formed with an aperture extending axially thereof to receive an oscillatory shaft provided at 50 its lower end with a T arm, one branch of

the said arm serving as a carrier for the second thread laying implement and the other branch arm being connected with and serving to transmit a rocking motion to the companion carrier. The upper end of the oscillatory shaft has clamped thereon an apertured crank arm which is actuated through a sliding connection with a crank-stud on the actuating shaft. When the presser-bar is elevated to raise the presser-foot above the 60 work, the thread engaging implements and all of the driving parts therefor are bodily lifted with the bar without disturbing their relative positions.

In the drawings, Figure 1 is a partly sectional front elevation of a machine embodying the improvements, and Fig. 2 is a front end elevation, thereof with the face-plate of the bracket-arm removed, the presser-bar being shown partly in section. Fig. 3 is a 70 perspective view of the stitch-forming and thread-laying mechanism. Fig. 4 is a detail view of the thread laying implements, their carriers and certain other connected parts, and Fig. 5 is a perspective view showing the 75 stitch and the manner in which the thread laying implements coöperate in forming the 80 same.

The improvements are embodied in a machine constructed with the usual base 1, hollow standard 2 and tubular overhanging arm 3 in the head 4 of which is journaled the vertically-reciprocating needle-bar 5 provided, in the present instance, with the multiple needle-clamp 6 carrying the two eye-pointed 85 needles 7.

The longitudinally arranged main or driving shaft 8 is journaled in suitable bearings in the base 1 beneath the work-plate 10 and is provided near its rearward end with an 90 actuating crank 9, and in practice receives its motion from the usual pulley mounted upon its rearward end.

The needle-actuating rock-shaft 11 is journaled in suitable bearings within and longitudinally of the overhanging bracket-arm and carries at its forward end a collar 12 formed with the crank-arm 13 provided with the crank-pin 13^a connected by means of the usual link 14 with a rearwardly projecting 100 stud carried by the collar 15 fixed upon the needle-bar 5, through which connections the needles receive their operative movements 105 from the rock-shaft 11. The needle-actuating rock-shaft has fixed upon its rearward 110

end a collar with oppositely extending crank-arms 16 and 17, the former of which is connected by means of the pitman-rod 18 with the crank 9 of the driving shaft from which the needle-actuating rock-shaft derives its 5 rocking movements. The second crank-arm 17 is connected by means of the pitman 19 with the rearwardly extending arm 20 of an elbow-lever mounted upon the transverse 10 fulcrum-pin 21 and having an upwardly extending arm 22 connected by means of the pitman 23 with the rocking looper-carrier 24, upon which are secured the lower-thread carrying looper 25 and adjacent needle-guard 26. 15 Fixed upon the main-shaft is the feed-actuating eccentric 27 embraced by the strap 28 of an eccentric-rod connected with the feed-rocker 29 which is journaled upon the fulcrum-pin 30 and has pivotally connected 20 thereto the rearward end of the feed-bar 31 carrying the feed-dog 32. The main-shaft has fixed thereon the feed-lifting eccentric 33 upon which is fitted the slide-block 34 embraced by the depending yoke 35 of the feed-bar 31 by means of which rising and 25 falling movements are imparted to the feed-dog 32.

Journalized in the head of the overhanging arm and parallel with the needle-bar is the 30 presser-bar 36 having clamped thereon near its lower end by means of the screw 37 the split collar of a bracket 38 having a depending arm 39 embraced by the shank 40 of the presser-foot 41, a set-screw 42 serving to 35 hold the shank in position. The bracket 38 is formed with a lateral arm 38^x apertured to receive a depending stud 43 serving as a pivotal support for a rocking carrier 44, the lower wall of the carrier resting upon the 40 head 42^x on the stud 43, the stud being secured in position upon the bracket-arm 38^x by means of a set-screw 45. Carrier 44 is provided near its free end with a vertical aperture adapted to receive the shank *a*^x of 45 the thread laying implement *a* which is secured in adjusted position by means of the set-screw 46. The second thread-laying implement *b* is provided with a carrier so arranged that its movements are utilized to 50 transmit motion to its companion carrier 44, in the manner now to be described.

Fitted within an aperture *o* formed axially of the presser-bar, is an oscillatory shaft 47 which projects below the collar of bracket 38 55 and on which is secured by means of the set-screw 48 a radial-armed carrier 49, the arm *c* of the carrier being apertured near its end to receive the shank *b*^x of thread laying implement *b*, the latter being secured in adjusted position by means of the set-screw 50. The second arm *d* of the carrier 49 is utilized 60 as a crank member to transmit motion to rock-arm 44, and therefore carrier 44 is provided with an open slot or recess 51 which 65 receives the end of carrier arm *d*, a pin 52

serving as a pivotal connection between the two.

The presser-bar is formed in two sections, the upper section 36^x being connected to the lower section by means of a connector *f*. 70 The connector is provided with upper and lower sleeves separated by a cut-away portion 53^x. The lower section of the presser-bar is clamped within the lower sleeve 53 of the connector and the upper section 36^x of the presser-bar is reduced in diameter to snugly fit into the reduced diameter of the upper connector sleeve 54 which also receives the upper end of the oscillatory shaft 47 as shown in Fig. 2.

Clamped upon that portion of oscillatory shaft 47 exposed by the intermediate cut-away portion 53^x of connector *f* is the split-collar 56 of a horizontally disposed crank arm 57 formed with a depending socket member 58 forming a part of a sliding connection between a crank-disk on the actuating shaft and the oscillating shaft 47. The socket member 58 receives a slide-pin 59 formed with an apertured cross-head 59^x embracing crank-stud 60 on the collar 12 fixed upon the actuating shaft.

In the arcuate movement of crank-stud 60 pin 59 will have a slight idle movement within the socket 58 to permit a dwell of the thread laying implements to hold the cross thread or threads in position during the descent of the needles and until the latter reach the work, and subsequently will be swung bodily back and forth by the oscillation of the actuating shaft to impart a corresponding backward and forward movement of the thread laying implements in the repositioning of the cross-thread.

Having thus set forth the nature of the invention, what I claim herein is:—

1. In a sewing machine, the combination with stitch-forming mechanism, of an end-wise movable supporting-bar, and a thread-carrier mounted to oscillate thereon; a second thread-carrier operatively connected with the first named thread-carrier, an oscillatory shaft carried by said bar and affording an axial support for the second thread-carrier, and means for imparting operative movements to the said oscillatory shaft.

2. In a sewing machine, the combination with stitch-forming mechanism, of a supporting-bar formed with an axial aperture and a thread-carrier mounted to oscillate thereon, a second thread-carrier operatively connected with the first named thread-carrier, an oscillatory shaft fitted within the aperture of the said bar and affording an axial support for the second thread-carrier, and means for imparting operative movements to the said oscillatory shaft.

3. In a sewing machine, the combination with stitch-forming mechanism, of means for laying the thread in front of the needle

or needles comprising a thread-carrier, an oscillatory shaft affording an axial support for the thread-carrier, an apertured crank-arm carried by said oscillatory shaft, a rock-shaft and a crank-stud carried thereby, and a slide-pin fitted within the aperture of the crank-arm and having a sleeve embracing the said crank-stud.

4. In a sewing machine, the combination with an actuating shaft and stitch-forming mechanism including a plurality of needles and means for reciprocating the same, of a presser-bar formed with an axial aperture, a shaft fitted to oscillate within the said aperture, a thread-carrying implement adapted to lay thread across the path of the needles, a rocking carrier for the said implement supported upon the oscillatory shaft, and a pin-and-socket sliding connection between the said oscillatory shaft and the said actuating shaft.

5. In stitch-forming mechanism for sewing machines, the combination with a plurality of reciprocating needles of a presser-bar formed with an axial aperture, an oscillatory shaft fitted within the aperture of the presser-bar, a thread carrying implement, a rocking carrier for the said implement mounted on the lower end of the oscillatory shaft, a crank-arm carried by the oscillatory shaft at its upper end and formed with a socket, a pin slidingly fitted within said socket and provided with an apertured cross-head, a rock-shaft operatively connected with the needles, and a crank-stud mounted upon the said shaft and embraced by the apertured cross-head of the sliding pin.

6. In stitch-forming mechanism for sewing machines, the combination with a plu-

rality of needles and means for reciprocating the same, of a thread-carrying implement, an oscillatory shaft, a rocking carrier fixed upon said shaft and formed with an arm, a thread laying implement supported by the carrier, a second thread laying implement and a rocking carrier therefor, an operative connection between the latter carrier and the arm of the first carrier, and means for imparting operative movements to the said oscillatory shaft.

7. In a sewing machine, the combination with a bed and an arm overhanging the same, of an actuating shaft supported by said arm, a needle-bar mounted in the head of the arm and operatively connected with the actuating shaft, an oscillatory shaft mounted in the head parallel with the needle-bar, a thread laying implement carried by the said oscillatory shaft, a crank-arm on the said oscillatory shaft, a crank-stud on the actuating shaft, and a sliding driving connection between the crank-arm and stud.

8. In a sewing machine, the combination with stitch-forming mechanism, of a thread-carrier and an oscillatory shaft upon which the same is mounted, a presser-bar comprising a lower section formed with an axial aperture to receive the oscillatory shaft, and an upper section, a connector formed with spaced sleeves to receive the sections of the presser-bar and expose the oscillatory shaft between them and actuating means connected to the said exposed portion of the oscillatory shaft.

In testimony whereof, I have signed my name to this specification.

ALBERT H. DE VOE.
